The ornamental design for a razor package label, as shown and described.

DESCRIPTION

FIG. 1 is a perspective view of a design for a razor package label according to a third embodiment of the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The dash broken lines are directed to the environment and are for illustrative purposes only and form no part of the claimed design.
